CLAIM

The ornamental design for the compression sleepwear, as shown and described.

DESCRIPTION

FIG. 1 is a front perspective view, titled forward to show an entrance of the compression sleepwear incorporating my new design;

FIG. 2 is a front view thereof;

FIG. 3 is a rear view thereof;

FIG. 4 is a left side view thereof;

FIG. 5 is a right side view thereof;

FIG. 6 is a front perspective view thereof with a leg slit partially opened;

FIG. 7 is a front perspective view thereof;

FIG. 8 is a top plan view thereof; and,

FIG. 9 is a bottom plan view thereof.

The broken lines illustrate portions of the compression sleepwear that form no part of the claimed design.

1 Claim, 6 Drawing Sheets
